UNITED STATES PATENT OFFICE.

ISAAC LEVY, OF CLEVELAND, OHIO.

DESIGN FOR A FAUCET-BODY.

SPECIFICATION forming part of Design No. 30,893, dated May 30, 1899.

Application filed April 17, 1899. Serial No. 713,411. Term of patent 7 years.

To all whom it may concern:

Be it known that I, ISAAC LEVY, a citizen of the United States, residing at Cleveland, in the county of Cuyahoga and State of Ohio, have invented and produced a new and original Design for a Faucet-Body, of which the following is a specification, reference being had to the accompanying drawings, forming a part thereof.

My invention relates to a new design for the body of a faucet, illustrated in the accompanying drawings, wherein—

Figure I is a perspective view. Fig. II is a forward end elevation.

The leading feature of my design for the body of the faucet consists in the peculiar external formation or configuration of the body next rearward of the spout 1. The said body next rearward of member 1 has its upper external surface 2 and its lower external surface 3 arranged horizontally and parallel, and each side of the said body has three external sides 4, 5, and 6—that is, the body has two perpendicular external sides 5 and 5 at opposite sides, respectively, of the body and somewhat farther apart than the side edges of the surfaces 2 and 3. An inclined side 4 extends upwardly and inwardly from the top of each perpendicular side 5 of the top horizontal surface 2, and another inclined side 6 extends inwardly and downwardly from the bottom of each perpendicular side 5 to the lower horizontal surface 3. The horizontal surfaces 2 and 3 are about twice the width of the surfaces 4, 5, and 6. The perpendicular surfaces

5 correspond or approximately correspond in width to the oblique surfaces 4 and 6.

An upward projection 7 is formed centrally of the upper horizontal surface 2.

At the rear end of the sides 2, 3, 4, 5, and 6 the body is provided with an annular groove 8, and rearward of this groove the body is cylindrical, as at 9, and the cylindrical portion 9 terminates in the flaring portion 10.

I would have it understood, however, that the leading or characteristic features of my design are specifically set forth in this description, and include, essentially, the eight surfaces 2, 3, 4, 5, 5, and 6, formed upon the body next rearward of the spout; the horizontality of the upper and lower surfaces 2 and 3; the perpendicularity of the surfaces 5 and 5, and the latter's arrangement centrally of opposite sides, respectively, of the body, the two surfaces 4 and 4 extending upwardly and inwardly from the different perpendicular surfaces 5 and 5, respectively, and the two surfaces 6 and 6 extending inwardly and downwardly from the different perpendicular surfaces 5 and 5, respectively.

What I claim is—

The design for a faucet-body, substantially as shown and described.

Signed by me, at Cleveland, Ohio, this 12th day of April, 1899.

ISAAC LEVY.
